UNITED STATES PATENT OFFICE.

ASA R. WELLS, OF SAN FRANCISCO, CALIFORNIA.

WOOD-PLANING MACHINE.

SPECIFICATION forming part of Letters Patent No. 247,788, dated October 4, 1881.

Application filed June 22, 1881. (No model.)

To all whom it may concern:

Be it known that I, ASA R. WELLS, of the city and county of San Francisco, in the State of California, have invented certain new and useful Improvements in Planing-Machines; and I do hereby declare that the following is a full, clear, and exact description thereof, reference being had to the accompanying drawings.

Planing-machines have heretofore been made with a single pair of uprights, to which the cutter-head and the various attachments for guiding and holding the lumber were secured. In the manufacture of these machines the height of the standards was regulated according to the maximum thickness of the timbers the machine was intended to plane, and the cost of the machines was increased in proportion to their capacity in this respect.

The planing-machine most usually employed in wood-working factories and shops is capable of planing timbers up to about twelve to sixteen inches only in thickness, because it is seldom that timbers of larger size require to be planed, and, besides increased first cost, the large machine is a constant consumer of extra power. It would not, therefore, pay to keep on hand one of the larger and more costly machines merely for doing this work.

My invention relates to a simple and inexpensive attachment to the medium-sized planing-machine above referred to, by means of which timbers of any desired size can be planed upon the same machine, all as herein-after more fully specified.

Referring to the accompanying drawings, Figure 1 is a side elevation of a portion of the frame of the machine, showing the manner of applying my invention to planing timbers of the medium size. Fig. 2 shows the same adapted to plane large-sized timbers. Fig. 3 is a cross-section through the line *x*, Fig. 2.

Let *A* represent the bed or frame of an ordinary planing-machine, such as is used in wood-working mills, factories, and shops for planing boards and timbers up to any prescribed thickness.

B represents one of the standards to which the cutter-head *C* and other attachments are secured. There are two of these standards,

one on each side of the machine, so as to form 50 a pair, and the cutter-head extends across from one to the other. In the drawings, Figs. 1 and 2, only one of these standards can be seen.

D is the carriage on which the board or timber is carried along under and against the cutter-head, and *F* is the pulley from which the cutter-head is driven by the belt *G*.

As above stated, the cutter-head *C* can be adjusted on the standards *B* to plane boards and timbers up to a specified maximum thickness; but if the timber should exceed this limit in thickness, the machine would be incapable of planing it, were it not for the attachment that I have added to it. This attachment consists of a pair of supplemental standards, *H*, of 65 greater height than the standards *B*, one on each side of the machine. These standards are secured to the frame or bed *A* of the machine on the side of the driving-pulley *E* opposite that on which the standards *B* are secured, and at a nearly-equal distance from the driving-pulley. The manner of attaching these supplemental standards is immaterial, so long as they are firm and rigid; but in practice I secure their lower ends to the bed *A*, while their 75 upper ends are attached to and braced from the ceiling, or from a cross-beam overhead, which forms a part of the mill structure. This gives additional steadiness to the planing-machine. In these supplemental uprights I form 80 seats *K* at the desired height, in which the ends of the frame of the cutter-head can be fitted and secured by bolts *ll*.

In planing small stuff, such as can pass under the cutter-head when it is attached to the 85 original standards *B*, I do not use the supplemental uprights; but when a piece of timber is to be planed which is too large to pass under the cutter-head when thus mounted, I detach the cutter-head from the standards *B* and 90 secure it to the supplemental standards *H*. In this case the bonnet with its presser-rolls and other attachments are not required, as the weight of the large timber is sufficient to keep it down on the carriage. The same driving- 95 belts will answer for driving the cutter-head when it is attached to either of the standards. To adjust the timber to the cutter-head so that

it will be in the proper position for planing, I block it up on the carriage until its upper face is brought to the desired position, thereby adjusting the timber to the head, instead of the head to the timber.

R R, in Fig. 2, shows the blocks upon which the large timber S rests. These blocks are temporary, and can be removed and others of a different thickness substituted for them, according to the necessities of the case.

By this means I render the medium or small sized planing-machine capable of doing large work, so that comparatively inexpensive and light-running machines will do the work of the largest and most costly machines, and at the same time the supplemental standards, when applied in the particular manner herein represented, form braces that greatly benefit the machine under all circumstances by making it more steady and permanent.

Having thus described my invention, what I claim, and desire to secure by Letters Patent, is—

1. A planing-mill having two sets of stand-

ards, the shorter having an adjustable support for the cutter-head, and the longer having a single seat for supporting the cutter-head, and adjusting-blocks resting upon the carriage, combined with suitable framing, substantially as set forth.

2. In a planing-machine having uprights attached to the framing, and a driving-pulley located between the pairs of uprights in such a position as to allow the same belt to work either cutter-head, the elevated braces described joining the higher uprights on either side, and spreading outward and upward and finding attachment to the beams in the building above for the purpose of stiffening said standards and giving an even action to the cutter-heads, substantially as set forth.

In witness whereof I have hereunto set my hand and seal.

ASA R. WELLS. [L. S.]
